UNITED STATES PATENT OFFICE.

HENRY BRAMMER, OF ST. LOUIS, MISSOURI.

MECHANICAL MOVEMENT.

No. 886,758.

Specification of Letters Patent.

Patented May 5, 1908.

Application filed June 27, 1907. Serial No. 381,094.

To all whom it may concern:

Be it known that I, HENRY BRAMMER, a citizen of the United States, and a resident of St. Louis, in the State of Missouri, have invented certain new and useful Improvements in Mechanical Movements, of which the following is a full, exact, and complete description.

My invention relates to mechanical movements, particularly for operating rotary washing machines, churns, etc., and its object is to convert the continuously revolving motion of the drive-shaft into a rotary reciprocating motion of the stirrer-shaft, and do this so that the greatest power can be imparted through the converting mechanism to the stirrer-shaft with the least expenditure of physical effort, and with a comparatively noiseless action at the moment the reversal of movement takes place, and at a variable speed, so as to produce as varied action of the stirrer-shaft and coacting elements in the tub of the washing machine, as possible. This I accomplish by the means hereinafter fully described, and as particularly pointed out in the claims.

In the drawings: Figure 1 is a side elevation of my invention. Fig. 2 is a view showing one side of the mangle gear. Fig. 3 is a partial view of the arched portion of the supporting frame showing the slotted part thereof.

In the drawings A represents the base-plate of a supporting-frame which, at one end, has a suitable post arising therefrom that is provided with bearings *a* for the permanently journaled portion *B* of the drive-shaft, and at the other end has one end of an arched portion *C* of said supporting-frame springing therefrom. This arched portion bridges over the mechanism that converts the continuously rotation of the drive-shaft into a rotary reciprocal motion of the stirrer-shaft, and the other leg of said arched portion terminates and merges into the base-plate, about its center of length, and is provided with a vertical slot *b* for the guidance of the vertical vibrations of the floating section *B'* of the drive-shaft. This floating section *B'* extends through said slot and has one end connected by a suitable universal joint *D* to the contiguous end of the permanently journaled portion *B*, and has its opposite end provided with a suitable spur-wheel *d*, that engages the pins of a segmental series of pins *e* projecting from the adjacent face of a

mangle-wheel *E*. Wheel *E* is secured to the end of a short shaft *F*, which extends in the same direction as the portion *B* of the drive-shaft, but in a plane above the same and is journaled in suitably elongated bearings integral with the leg of the arched portion *C* of the supporting-frame opposite the leg in which slot *b* is made.

The segmental series of pins *e* are arranged concentric to the center of the mangle-wheel, and has an endless groove or runway *g* in its face which surrounds the base of said pins, and is, at every point throughout its length, an equal distance removed from an imaginary line struck from the center of the mangle wheel and intersecting the centers of said pins. The end of the floating portion of the drive-shaft extends beyond the face of the spur-wheel, and, if desired, has an anti-friction roller *d'* journaled thereon that enters said runway *g*, and keeps the spur-wheel in engagement with said pins, and when said spur-wheel rotates the mangle-wheel in a given direction until it reaches the end pin *e* of the series, *e*, causes said spur-wheel to reverse the motion of the mangle-wheel, and pass to and engage the portions of the pins nearer the center of rotation of the wheel, or pass to and engage the portion of the pins farthest from the said center, which the floating member of the drive-shaft, by rising or falling, permits the spur-wheel to do, and thus, because of the fact that the uppermost segment of the spur-wheel travels in one direction while the opposite or lowest segment travels in the opposite direction, causes said mangle-wheel to rotate first in one direction and then the other.

The side of the mangle-wheel opposite that from which the pins *e* project has an integral beveled gear *G* concentric therewith, and this pinion meshes with a beveled pinion *J* on the upper end of a vertical shaft *H* which is journaled in bearings *I* at the base of the leg of the arched portion of the supporting-frame farthest from the drive-shaft and rotates said shaft *H* first in one direction and then the other.

What I claim as new is:

1. The combination with a continuously revolving drive-shaft, of a rotary reciprocal mangle-wheel engaged thereby journaled in stationary bearings, and a rotary reciprocal shaft arranged perpendicular to the axis of said mangle-wheel and actuated thereby.
2. The combination with a vibratory

floating continuously revolving drive-shaft, of a rotary reciprocal mangle-wheel engaged thereby journaled in stationary bearings, and a rotary reciprocal shaft arranged perpendicular to the axis of said mangle-wheel and actuated thereby.

3. The combination with a continuously revolving drive-shaft consisting of a portion journaled in stationary bearings and a vibratory floating portion connected to said first mentioned portion by a universal joint, of a rotary reciprocal mangle-wheel engaged thereby journaled in stationary bearings, and a rotary reciprocal shaft arranged perpendicular to the axis of said mangle-wheel and actuated thereby.
- 10 15

4. The combination with a continuously revolving shaft, of a rotary reciprocal mangle-wheel whose shaft is journaled in stationary bearings, and one side of which is engaged by said drive-shaft and the opposite side provided with an integral gear, and a rotary reciprocal shaft arranged perpendicular to the axis of the mangle-wheel and 20 25 a pinion on its adjacent end engaged by said gear.

5. The combination with a vibratory floating continuously revolving shaft, of a rotary reciprocal mangle wheel whose shaft is journaled in stationary bearings, and one side of which is engaged by said drive-shaft and the opposite side provided with an integral gear, and a rotary reciprocal shaft arranged perpendicular to the axis of the mangle-wheel and a pinion on its adjacent end engaged by said gear.

6. The combination with a vibratory floating continuously revolving shaft consisting of a portion journaled in stationary bearings and a vibratory floating portion connected to said first mentioned portion by a universal joint, of a rotary reciprocal mangle wheel whose shaft is journaled in stationary bearings, and one side of which is engaged by said drive-shaft and the opposite side provided with an integral gear, and a rotary reciprocal shaft arranged perpendicular to the axis of the mangle-wheel and a pinion on its adjacent end engaged by said gear.

40 45 50 55 60 65

7. The combination with a continuously revoluble drive-shaft consisting of a portion journaled in stationary bearings, and a vibratory floating portion connected by a universal joint to said first mentioned portion and a spur-wheel on its opposite end, of a rotary reciprocal mangle wheel having a segmental series of concentrically arranged pins projecting from one side that are engaged by said spur-wheel, and a rotary reciprocal shaft arranged perpendicular to the axis of said mangle-wheel and actuated thereby.

8. The combination with a continuously revoluble drive-shaft consisting of a portion

journaled in stationary bearings and a vibratory floating portion connected by a universal joint to said first mentioned portion, and a spur-wheel on its opposite end, of a rotary reciprocal mangle-wheel having a 70 75 segmental series of concentrically arranged pins projecting from one side that are engaged by said spur-wheel, an integral gear on the other side, and a rotary reciprocal shaft arranged perpendicular to the axis of said mangle-wheel and a pinion on its adjacent end engaged by said gear and actuated thereby.

9. The combination of a gear having flat parallel sides or faces, a segmental rack projecting from one of said sides and a circular rack projecting from the other of said sides, a gear adapted to mesh with said circular rack, a driven shaft adapted to be actuated by said gear, a pinion adapted to engage 80 85 said segmental rack, a driving shaft adapted to actuate said pinion, and an elongated bearing adapted to support said driving shaft and permit said pinion to pass from one side of said segmental rack to the other 90 side thereof.

10. The combination with a continuously revolving drive-shaft, of a rotary reciprocal mangle-wheel engaged thereby journaled in stationary bearings, and a rotary reciprocal shaft actuated by said wheel.

11. The combination with a vibratory floating continuously revolving drive-shaft, of a rotary reciprocal mangle-wheel engaged thereby journaled in stationary bearings, 100 and a rotary reciprocal shaft actuated by said wheel.

12. The combination with a continuously revolving drive-shaft consisting of a portion journaled in stationary bearings and a vibratory floating portion connected to said first mentioned portion by a universal joint, of a rotary reciprocal mangle-wheel engaged thereby journaled in stationary bearings, and a rotary reciprocal shaft actuated by 105 110 115 said wheel.

13. The combination with a continuously revolving shaft, of a rotary reciprocal mangle-wheel whose shaft is journaled in stationary bearings, and one side of which is engaged by said drive-shaft and the opposite side provided with an integral gear, and a rotary reciprocal shaft and a pinion on its adjacent end engaged by said gear.

120 125

14. The combination with a vibratory floating continuously revolving shaft, of a rotary reciprocal mangle-wheel whose shaft is journaled in stationary bearings, and one side of which is engaged by said drive-shaft and the opposite side provided with an integral gear, and a rotary reciprocal shaft and a pinion on its adjacent end engaged by said gear.

15. The combination with a vibratory floating continuously revolving shaft con-

sisting of a portion journaled in stationary bearings and a vibratory floating portion connected to said first mentioned portion by a universal joint, of a rotary reciprocal mangle wheel whose shaft is journaled in stationary bearings, and one side of which is engaged by said drive-shaft and the opposite side provided with an integral gear, and a rotary reciprocal shaft and a pinion on its adjacent end engaged by said gear.

16. The combination with a continuously revoluble drive-shaft consisting of a portion journaled in stationary bearings, and a vibratory floating portion connected by a universal joint to said first mentioned portion and a spur-wheel on its opposite end, of a rotary reciprocal mangle-wheel having a segmental series of concentrically arranged pins projecting from one side that are engaged by said spur-wheel, and a rotary reciprocal shaft actuated by said wheel.

17. The combination with a continuously revoluble drive-shaft consisting of a portion journaled in stationary bearings, and a vibratory floating portion connected by a universal joint to said first mentioned portion, and a spur-wheel on its opposite end, of a rotary reciprocal mangle-wheel having a segmental series of concentrically arranged pins projecting from one side that are engaged by said spur wheel, an integral gear on the other side, and a rotary reciprocal shaft and a pinion on its adjacent end engaged by said gear and actuated thereby.

In testimony whereof I have hereunto set my hand and seal this 12th day of June, A. D., 1907.

HENRY BRAMMER. [L. s.]
